US00D769281S

(12) **United States Design Patent** (10) Patent No.: **US D769,281 S**
 (45) Date of Patent: **** Oct. 18, 2016**

(54) **DISPLAY SCREEN WITH GRAPHICAL USER INTERFACE**

(71) Applicant: **P&W Solutions Co., Ltd.**, Tokyo (JP)

(72) Inventor: **Toshiyuki Omiya**, Tokyo (JP)

(73) Assignee: **P&W SOLUTIONS CO., LTD.**,
Shinagawa-Ku, Tokyo (JP)

(**) Term: **14 Years**

(21) Appl. No.: **29/517,130**

(22) Filed: **Feb. 10, 2015**

Related U.S. Application Data

(62) Division of application No. 29/433,390, filed on Sep. 28, 2012, now Pat. No. Des. 727,342.

(30) **Foreign Application Priority Data**

Jun. 5, 2012 (JP) 2012-013377
 Jun. 5, 2012 (JP) 2012-013378
 Jun. 5, 2012 (JP) 2012-013379

Assistant Examiner — Shannon Morgan

(74) Attorney, Agent, or Firm — Muncy, Geissler, Olds & Lowe, P.C.

(57) **CLAIM**

The ornamental design for a display screen with graphical user interface, as shown and described.

DESCRIPTION

The FIGURE is a front view of a display screen with graphical user interface showing my new design.

The broken lines in the FIGURE showing portions of the display screen and graphical user interface form no part of the claimed design.

1 Claim, 1 Drawing Sheet
